[57] CLAIM

The ornamental design for a rechargeable light and night-light, as shown and described.

DESCRIPTION

FIG. 1 is a front elevational view of a rechargeable light and nightlight showing my new design;

FIG. 2 is a top plan view thereof;

FIG. 3 is a rear elevational view thereof, with a movable plug being in a first position relatively flush with the rechargeable light and nightlight's body;

FIG. 4 is a bottom plan view thereof;

FIG. 5 is a side elevational view of the left side of the rechargeable light and nightlight design;

FIG. 6 is a side elevational view of the right side of the rechargeable light and nightlight design;

FIG. 7 is a perspective view of the rechargeable light and nightlight design, showing the front, top and left sides of the design;

FIG. 8 is a perspective view of the rechargeable light and nightlight design, showing the rear, top and left sides of the design;

FIG. 9 is a top plan view of a second configuration of design in which the movable plug is in a second position protruding from the back surface of the rechargeable light and night-light;

FIG. 10 is a rear elevational view of the second configuration of the rechargeable light and nightlight design;

FIG. 11 is a side elevational view of the right side of the rechargeable light and nightlight in the second configuration; and,

FIG. 12 is a perspective view of the rechargeable light and nightlight in the second configuration, showing the rear, top and left sides of the design.
